UNITED STATES PATENT OFFICE.

THOMAS J. O'BRIEN, OF BUFFALO, NEW YORK.

DESIGN FOR A TRAP FOR SEWERS.

SPECIFICATION forming part of Design No. 29,420, dated September 27, 1898.

Application filed June 4, 1898. Serial No. 682,607. Term of patent 14 years.

To all whom it may concern:

Be it known that I, THOMAS J. O'BRIEN, residing at Buffalo, in the county of Erie and State of New York, have invented and produced a new and original Design for a Trap for Sewers or Similar Articles, of which the following is a specification, reference being had to the accompanying drawings, showing a part thereof.

- 10 Figure 1 represents a perspective view of the trap. Fig. 2 represents an end elevation of the same. Fig. 3 represents a vertical longitudinal section on or about line *b b*, Fig. 4, showing a side elevation outline of the body and the several parts of the trap. Fig. 4 represents a top plan view of the trap. Fig. 5 represents a transverse vertical section showing the shape of the body of the trap in cross-section.
- 15 The leading feature of my design consists in the unitary article made the subject of illustration and presents to an exterior view substantially the appearance shown in Figs. 1, 2,

and 4, the top 1 having two circular openings 2, each provided with a surrounding rim 3 and sloping or curving downward on all sides from the said openings, the pipes 4 extending in a substantially horizontal direction from the trap-body slightly below the top and the curved side walls 5 converging gradually toward each other and terminating in the substantially flat bottom 6.

An interior view of the trap reveals a substantially vertical wall or partition 7, which extends from the top nearly to the bottom of the interior of the trap and divides into two equal or nearly equal compartments connected at the bottom. (See Fig. 3.)

What I claim is—

The design for a trap for sewers or similar articles, substantially as herein shown and described.

THOS. J. O'BRIEN.

Witnesses:

G. A. NEUBAUER,
A. J. SANGSTER.
